UNITED STATES PATENT OFFICE.

SAMUEL R. BAILEY, OF AMESBURY, MASSACHUSETTS.

CARRIAGE-SPRING.

SPECIFICATION forming part of Letters Patent No. 681,094, dated August 20, 1901.

Application filed May 10, 1901. Serial No. 59,547. (No model.)

To all whom it may concern:

Be it known that I, SAMUEL R. BAILEY, a citizen of the United States, residing at Amesbury, in the county of Essex and State of 5 Massachusetts, have invented new and useful Improvements in Carriage-Springs, of which the following is a specification.

This invention relates to improvements in carriage-springs for vehicles; and it consists 10 in improved means for connecting the ends of the leaf or elliptic springs, as will herein-after be more fully shown and described, reference being had to the accompanying drawings, wherein—

15 Figure 1 represents a side elevation of a carriage-spring, showing its ends connected by my improved device. Fig. 2 represents an enlarged top plan view of one of the ends of the upper spring and its connection to the 20 lower spring. Fig. 3 represents a bottom plan view of Fig. 2. Fig. 4 represents a central longitudinal section on the line 4 4, shown in Fig. 2. Fig. 5 represents a longitudinal section on the line 5 5, shown in Fig. 2. Fig. 25 6 represents a horizontal section on the line 6 6, shown in Fig. 4. Fig. 7 represents a cross-section on the line 7 7, shown in Fig. 4. Fig. 8 represents a detail top plan view of the upper spring, and Fig. 9 represents a detail 30 top plan view of the lower spring.

Similar letters refer to similar parts wherever they occur on the different parts of the drawings.

In Fig. 1, A and B represent, respectively, 35 the upper and lower leaves of an elliptic or leaf vehicle-spring, to which are respectively attached the additional leaf-springs a a and b b, as is usual in this kind of carriage-springs. One of the springs, preferably the 40 upper one, A, is hooked at its ends at A' for the purpose of receiving the ends of the lower spring B, which are thus caused to be received in and to bear against the inner portion of the hooks A' of the upper spring A, as shown 45 in the drawings.

C is a semicircular (or nearly so) socket, adapted to inclose the ends of the upper and lower springs A B, as shown, such socket having circular closed end pieces C' C' made integral with said socket and serving as abutments for preventing a lateral motion of the 50 respective springs.

In practice I prefer to make on the inner portion of the socket C a pin or projection C'', adapted to be received in a perforation A' 55 in the upper spring A, as shown, and by such arrangement the ends of the upper spring A are suitably interlocked with and connected to the sockets C, as shown, thus preventing detachment of said sockets from the ends of 60 the springs.

If so desired, the ends of the upper spring A may be riveted to the sockets C or otherwise connected thereto without departing from the essence of my invention. 65

Integral with or attached to the closed end pieces C' C' are inwardly-projecting pins C³ C³, adapted to be received in side recesses B' B' on the lower spring for the purpose of holding the said lower spring interlocked 70 relative to the sockets C C and allowing said lower spring to yield relative to the upper one when in use on the vehicle.

For the purpose of lubricating the bearing of the end of the lower spring relative to the 75 interior of the hooked end of the upper spring I make on the interior of each socket C a cavity C⁴, adapted to contain one or more wicks D, wholly or partially inserted in perforations A⁸ A⁸ in the hooked ends of the upper spring A, as shown in Figs. 5 and 8. The 80 said wicks may be suitably charged with any well-known lubricant from time to time as needed.

The invention is very simple in construction and serves as a strong and durable means for yieldingly connecting the ends of carriage-springs, as hereinabove described. 85

What I wish to secure by Letters Patent and claim is— 90

1. The herein-described elliptic carriage-spring, consisting of an upper and a lower member, one of said members having hooked ends engaging the straight ends of the other members, in combination with socket-pieces 95 inclosing the ends of said members, said socket-pieces being connected to one of the members and having closed ends, and inwardly-projecting pins on the ends of the socket-pieces, the sides of the member unconnected to the socket-pieces being provided with recesses into which said pins project, substantially as specified. 100

2. The herein-described elliptic carriage-

spring consisting of an upper and a lower member, one of said members having hooked ends engaging the straight ends of the other members, in combination with socket-pieces inclosing the ends of the members and having closed ends, said socket-pieces being connected to one of said members and loosely interlocked with the other member and each provided with a lubricant-cavity, and a fibrous material disposed in said cavity, substantially as and for the purpose specified.

3. The herein-described elliptic carriage-spring consisting of an upper and a lower member, one of said members having hooked ends engaging the straight ends of the other

members, in combination with socket-pieces inclosing the ends of the members and having closed ends, said socket-pieces being provided with lubricant-cavities, and the said hooked ends of one of the members being perforated, and wicks arranged in said cavities and fitted in said perforations, substantially as and for the purpose specified.

In testimony whereof I have hereunto set my hand in presence of two subscribing witnesses.

SAMUEL R. BAILEY.
